UNITED STATES PATENT OFFICE.

DAVID RABANETE, OF BARCELONA, SPAIN.

CALCULATING MACHINE.

Application filed October 17, 1924. Serial No. 744,261.

To all whom it may concern:

Be it known that I, DAVID RABANETE, a subject of the King of Spain, residing at Barcelona, Spain, have invented certain new and useful Improvements in Calculating Machines, of which the following is a specification.

My invention refers to calculating machines and has for its object to provide a calculating machine, especially appropriate for carrying out operations of multiplication and division, which shall be simple in construction, economical in cost and capable of being constructed of a size sufficiently small to enable it to be carried in the pocket.

The invention consists in combining in a machine of this class a series of endless ribbons each one of which has printed on it following one after the other the multiplication tables corresponding to the numbers 2 to 9 inclusive.

These endless ribbons are mounted one alongside the other on pairs of pulleys or rollers and one of these pulleys is provided with a flange or other appropriate means to enable it to be turned by the fingers with the object of moving the ribbon.

The multiplication tables printed on each one of the ribbons have the figures distributed in three columns, the figure in the center column representing the multiplicands from 0 to 9 and the two columns to the right and left represent respectively the units and tens of the product of each one of these multiplicands multiplied by the multiplier corresponding to the table. The casing in which these ribbons are enclosed is provided with a series of slots each one of which is appropriate for allowing one line of all the ribbons to be seen and on the outside of the casing is indicated the number which constitutes the multiplier corresponding to the table which can be seen through this slot.

The invention will be fully understood by the detailed explanation which follows and with the help of the accompanying drawings in which:—

Fig. 1 is an outside plan view of the calculating machine showing the front face.

Fig. 2 is a similar view of the machine with the front cover removed.

Fig. 3 is a plan view of the back part of the machine.

Fig. 4 is a section of the machine on the line IV—IV of Figs. 1 and 2, and

Fig. 5 is a detail to an enlarged scale of a portion of one of the ribbons.

In the form of construction shown in the drawings, the machine is made up of a case 1 preferably of metallic sheeting which possesses on its front face four transverse slots 2 and on the back face an equal number of similar slots. These slots extend across the whole width of the machine and alongside them are painted at 3 the numbers from 2 to 9 which constitute the multipliers of the tables which can be seen through the corresponding slots.

In the inside of the case there is a series 70 of endless ribbons 4 which are arranged one alongside the other and are mounted upon rollers or pulleys 5 and 6 loosely mounted on the transverse axles 7, 8 in such a way that the pulleys 5, 6 corresponding to any particular one of the ribbons can be turned without the pulleys of the neighbouring ribbons being caused to revolve. In order to be able to turn these pulleys conveniently each of the lower pulleys 6 is provided on one of 75 its sides with an extension 9 of enlarged diameter in the form of a flange fixed to the pulley, which flange 9 protrudes through both sides of the machine through apertures 10 provided on the front and back 80 faces of the case, in such a way that it is easy to revolve the flange with the fingers from the outside of the case and thereby rotate the corresponding pulley 6 to move the corresponding ribbon 4.

Each one of the ribbons 4 has printed on it, the one following the other, the multiplication tables of the figures 2 to 9 inclusive, in the manner shown in Fig. 5, in which are seen the multiplication tables of 4 and 5 and 95 part of the tables of the figures 3 and 6.

Each one of these tables comprises the products of the corresponding multiplier multiplied by all the figures from 0 up to 9. These tables are divided into three columns; the figures of the central column represent the multiplicands and the figures of the columns to the right and left represent respectively the units and tens of the product of each one of these multiplicands multiplied by the multiplier corresponding to the particular table which multiplier is the figure painted or engraved at 3 alongside the corresponding slot. Thus, for example, in the table of the figure 5, which is that 100 indicated by the letter *a* in Fig. 5, the figures in the central column, 0, 1, 2, 3 . . . 9 rep-

resent the multiplicands while the figures in the other two columns read without that of the central column represent the product of each one of the figures of the central column multiplied by the figure 5, which is the multiplier in this case. In the same way are arranged all the other tables of all the ribbons.

Preferably, and with the object of facilitating the corresponding distinction between the figures, those of the central column are printed different in size from those of the two lateral columns or better still different in color, as for example, the figures in the central column are printed in red and those of the lateral columns in black.

Preferably the two inner sides of each of the endless ribbons are joined together by an inner ribbon 12 which limits the movement of the endless ribbon, so that it can travel only over the distance necessary to allow all the numbers of the corresponding table to appear in each one of the slots and thus prevent the numbers of the following or previous table from appearing in one of the slots.

As will be understood, the number of endless ribbons 4 corresponds to the maximum number of figures which may compose the multiplicand and therefore a greater or lesser number of ribbons are provided according to the capacity for which it is desired to construct the machine.

In order to obtain with this machine the product of a quantity made up of various figures, for example, 427, multiplied by a quantity composed of one figure, for example, 5, the flanges 9 corresponding to three of the ribbons are turned until in the slot corresponding to the figure 5, there appears read out of the figures in the centers of the three ribbons, the quantity 427, the multiplicand. The remaining ribbons may be arranged in such a way that the white space which occurs between each two consecutive tables is visible through the slot. In this case the three ribbons appear in the slot corresponding to the figure 5, as follows:

$$50 \quad 2(4)0 \quad 1(2)0 \quad 3(7)5$$

The central figures typed in parentheses are those which form the multiplicand and in the practical construction of the machine are printed in red or in any other manner which will make them stand out distinctly.

In this case the figures forming the product of 427 multiplied by 5 are obtained in the following manner: The units are 5, which is the unit of the right hand ribbon. The tens are formed by adding the figure 3, which represents the tens of the right hand ribbon, to the figure 0 which represents the units of the second ribbon; that is to say, 3 plus 0 = 3. The hundreds are formed by

adding the figure 1, which represents the tens of the second ribbon to the figure 0 which represents the units of the third, and, lastly, the thousands are only the figure 2, which represents the tens of the third ribbon.

Thus, in this case, the product of 427 multiplied by 5 comes out as 2,135.

It must be observed that as the middle figures in each one of the ribbons are printed in red or otherwise distinctively, it follows that each one of the figures of the product is obtained by adding the two black figures which are between each two adjacent red figures. This facilitates the operation very greatly since the two figures which are to be added together appear to view one alongside the other.

When it is desired to multiply a number composed of several figures by another also made up of several figures the procedure is to obtain the partial products resulting from multiplying the multiplicand by each one of the figures of the multiplier and afterwards effecting the sum total in the same way as when the calculation is made mentally.

In order to reduce the size of the machine, the tables of the multipliers 0 and 1, which are known to all, have been omitted.

This machine may also be used for carrying out division in a manner inverse to that employed when multiplying. If it is desired to divide by a single figure a beginning is made by establishing the dividend or the quantity the nearest possible to it, which is formed by summing the consecutive black figures between each two red figures and in this case the red figures represent the quotient of this quantity obtained by the divisor which is the figure printed or engraved in the slot.

When the divisor is made up of several figures it is more advantageous to proceed as follows: A beginning is made by establishing the divisor with the red figures on the ribbons and in each slot the black figures give the product of this divisor by the figure painted alongside the slot. It is then ascertained which of these products is nearest to the dividend and the figure corresponding to the slot is the first figure of the quotient. The product of the dividend is subtracted and by adding to it the figure following the second figure of the quotient is found, and by proceeding successively in the same manner.

I claim:

1. In a calculating machine, a case provided with a series of transverse slots each one of which corresponds to a figure which is a multiplier; a series of endless ribbons inside the case each one of which has printed upon it the multiplication tables with the products of the figure corresponding to each one of the slots multiplied by the figures

from 0 to 9, means for independently moving each one of these ribbons so that the product of the figure corresponding to a multiplier by any of the figures from 0 to 9, 5 can be made to appear in one of the slots.

2. In a machine for multiplication and division, a case having a series of transverse slots, a series of endless ribbons arranged side by side, two axles loosely carrying reels 10 upon which the endless ribbons are stretched, one of the reels of each ribbon being arranged for operation from outside the case for moving the endless ribbons, the 15 ribbons having tables printed upon them in each of which there is a central column formed by the figures 0 to 9 and two lateral columns which indicate the products of each one of such figures multiplied by a multiplier corresponding to the particular table. 20 3. In a machine for multiplication and division, a case having a series of transverse slots, a series of endless ribbons arranged

side by side, two axles loosely carrying reels upon which the endless ribbons are stretched, one of the reels of each ribbon 25 being arranged for operation from outside the case for moving the endless ribbons, the ribbons having tables printed upon them in each of which there is a central column formed by the figures 0 to 9 and two lateral 30 columns which indicate the products of each one of such figures multiplied by a multiplier corresponding to the particular table, a tie member connected across each of the endless ribbons to limit movement thereof. 35

4. In a calculating machine, a case, a movable endless ribbon in the case, characters carried by the ribbon and visible at times through the case, and a tie member connected across the ribbon to limit the 40 movement thereof.

In testimony whereof I affix my signature.

DAVID RABANETE.
